D. S. ROBINSON.
HOSE COUPLING.

No. 24,429.

Patented June 25, 1895.

FIG. 1.

FIG. 2.

ATTEST,

Dr. B. Moser.
N. M. Thomas.

INVENTOR

Dennis S. Robinson

B. F. H. Fisher

UNITED STATES PATENT OFFICE.

DARIUS S. ROBINSON, OF CLEVELAND, OHIO.

DESIGN FOR A HOSE-CO尤PLING.

SPECIFICATION forming part of Design No. 24,429, dated June 25, 1895.

Application filed May 17, 1895. Serial No. 549,722. Term of patent 7 years.

To all whom it may concern:

Be it known that I, DARIUS S. ROBINSON, a citizen of the United States, residing at Cleveland, in the county of Cuyahoga and State of Ohio, have invented and produced a new and original Design for a Hose-Coupling, of which the following is a specification, reference being made to the accompanying drawings, showing the parts thereof.

10 In the accompanying drawings, Figure 1 is a plain elevation of a hose-coupling, showing my design complete; and Fig. 2 is a longitudinal section of the coupling, which serves to more clearly disclose the peculiar outline 15 of the ornamental thread about the shank of the coupling.

The leading and characteristic feature of

my design is the shape and configuration of the surface of the main portion —A—, associated with the ornamental head —B—. The 20 portion —A— projects from the head in somewhat tapered lines, and is cylindrical in cross section and has twined about it a single spiral thread —2—, having the contour in cross section substantially of a capital letter —R—, 25 and disclosing a wide unoccupied portion —5— between the convolutions of the thread.

What I claim is—

The design for a hose coupling, substantially as set forth.

DARIUS S. ROBINSON.

Witnesses:

H. T. FISHER,
R. B. MOSER.
